VERTICALLY ADJUSTABLE PEDESTAL
STRUCTURE FOR DRAWING TABLES

Giovanni Zuzzi, Milan, Italy

Application April 23, 1952, Serial No. 283,907

3 Claims. (Cl. 311—39)

1

The invention relates to a pedestal structure and in particular to a structure which permits of lifting and lowering, respectively, of the same, as well as rotation thereof.

It was proposed before to make drawing tables which were equipped with means for lifting and lowering, respectively, the table and also with means for adjustment of the table at different angles, which means included traction or torsion springs and/or counterweights. These means were usually hand- or foot-operated. It was also proposed before to equip such drawing tables with hydraulic lifting devices which, however, likewise required manual operation.

The provision of springs and/or counterweights brought about a number of drawbacks and among them the necessity of providing a comparatively large space for the operative elements, the necessity of difficult labor particularly for heavier tables, interruption of the work by the draftsman for time-consuming adjustment of the table, and also wear of the springs and beams required for the proper operation of the adjustment device. In case a hydraulic lifting device is provided, all drawbacks inherent in such devices, as loss or freezing of the hydraulic fluid or other causes for inoperativeness are apparent. If the table has to be reset in accordance with the prevailing light conditions, the entire table, which is in most cases rather heavy, requires displacement to the best light conditions, particularly if the table is to be shifted from daylight to artificial light.

It is, therefore, one object of the present invention to provide a pedestal structure which avoids all the mentioned drawbacks, is of simple, economical structure, and permits of easy operation without any physical effort.

It is another object of the present invention to provide a pedestal structure which permits of easy lifting and lowering, respectively, thereof, as well as rotation of the board for 360°.

It is still a further object of the present invention to provide a pedestal structure which includes an electric motor and suitable coupling means for lifting, lowering and rotating the load carried by the structure in accordance with the specific requirements.

With these and other objects in view which will become apparent in the following detailed description, the present invention will be clearly understood in connection with the accompanying drawing in which:

Figure 1 is a rear elevation of the structure, parts of the housing being broken away for the purpose of better showing;

Fig. 2 is an end view thereof;

Fig. 3 is a fragmentary end view of the drive means;

2

Fig. 4 is a fragmentary rear view of the drive means; and

Fig. 5 is a fragmentary elevational view of the coupling means.

Referring now to the drawing, the pedestal structure comprises preferably a tripod 1 which carries a platform 2 to which a horizontally disposed bevelled gear 3 is permanently secured.

A vertical pin 4 extends centrally through the platform 2, which pin 4 secures a frame 5 rotatably to the platform 2, so that the frame 5 may rotate for an angle of 360° relative to the tripod 1. Ball bearings (not shown) may be provided between the frame 5 and the platform 2 in order to reduce the friction during the relative rotating movement.

A lower housing 6 is secured to and disposed on top of the frame 5 and an upper housing 7 is telescopically disposed over the lower housing 6. At least two columns 8 extend upwardly in the lower housing 6, which columns 8 are secured to the bottom and top plates 9 and 10.

A spindle 11 is rotatably mounted in the frame 5 and carries thread 12 on the greater part of its upwardly extending portion which is disposed within the lower housing 6. The support 13 of the spindle 11 permits of free rotation and prevents any axial movement thereof. The spindle 11 extends into a second hollow spindle 14 having inner thread 15 which spindle 14 is adapted to be raised and lowered respectively upon turning the spindle 11 in one or the other direction. A cross plate 16 is secured to the lower end of the spindle 14 and the cross plate 16 has oppositely disposed guides 17 which slide on the columns 8 during the lifting and lowering movement, respectively, of the spindle 14. The top plate 10 has secured thereto another guide member 18 through which the spindle 14 slides during its axial movement. Finally, special guide elements 19 are disposed between the outer housing 7 and the lower housing 6 in order to permit easy telescopic movement between the said two housings 6 and 7.

The lower end of the upper housing 7 is necessarily open in order to receive the lower housing 6, while its upper end is closed up by a plate 20 which is adapted to carry a bracket 21 to receive a horizontally disposed pivot 22.

In the application of the structure to a drawing board, a supporting frame 23 is carried by the pivot 22 by means of a clamping device 24 which maintains the supporting frame 23 in any angular position by means of a screw bolt 25. A lever 26 having a handle 27 is secured to the clamping device and extends in downward direction in order to permit of easy manual adjustment of the desired angular position for the board 28.

An electric motor 29 is properly supported on the platform 2 of the tripod 1 and the electric mo-

tor 29 drives over a belt drive 30 a horizontally disposed main shaft 31. Two bevelled gears 32 are rotatably mounted, oppositely disposed from each other, on the main shaft 31, and both gears 32 permanently mesh a third horizontally disposed bevelled gear 33 which is keyed to the lower end of the spindle 11. A clutch means, preferably a claw clutch 34, is keyed to the shaft 31 and adapted to be moved in axial direction either to the right or to the left in order to couple one of the bevelled gears 32. Thus, depending upon the bevelled gear 32 which joins the rotation of the shaft 31, due to the particular position of the clutch 34, the spindle 11 will be rotated in one or the other direction and bring about the lifting and lowering, respectively, of the column 14 and thereby of the drawing board 28.

The clutch 34 may be operated by a foot pedal 35 or by any other suitable means. If the clutch 34 is in neutral position, the electric motor 29 may be put into operation by means of a switch (not shown) and upon setting the clutch 34 only is it possible to start the lifting or lowering movement of the drawing board 28. Instead of providing inner thread in the spindle 14 substantially throughout its entire length, a box 36 having inner thread may be disposed at the lower end of the spindle 14 to bring about its lifting and lowering movement, respectively.

Relays 37 and 38 are disposed at the bottom and near the top of the upper housing 7, in order to open the motor circuit when the upper housing reaches the lowermost and uppermost position, respectively.

In order to bring about the rotating movement of the drawing table, the shaft 31 carries a gear 39, and a further shaft 40 is mounted in a chamber 41 covering the electric motor 29 with its drive. A gear 42 is keyed to the shaft 40 and a pinion 43 is also keyed to the shaft 40 which meshes the bevelled gear 3 of the platform 2. A coupling device, preferably operated by a pedal 44, is also secured to the chamber 41, which coupling device comprises a shaft 45 the ends of which carry epicycloidal gears 46 and 47, respectively. Depending upon the position of the coupling device and its pedal 44, the gear 39 meshes the epicycloidal gear 46 and the gear 42 the epicycloidal gear 47 in the coupling position of the device (shown in full lines in Fig. 3), or these gears 39 and 42 are out of mesh in the non-coupling position of the device (shown in dotted lines in Fig. 3). If they are in the meshing operative position, the pinion 43 will turn and rotate along the bevelled gear 3 and thereby turn the entire structure including the housings 6 and 7 for any required angle to 360° on the pivot 4.

While I have disclosed one embodiment of the present invention, it is to be understood that this embodiment is given by example only and not in a limiting sense, the scope of the invention being determined by the objects and the claims.

I claim:

1. A pedestal structure comprising a base, a first housing rotatably mounted on the said base, a second housing secured in superposed position to the said first housing and a third housing having a top plate, being open at its bottom and telescopically receiving the said second housing, a motor supported by the said base, gear means driven by the said motor disposed in the said first housing, a threaded spindle extending upwardly from the said first housing into the said second housing, the said threaded spindle being mounted in the said second housing for rotation

upon its longitudinal axis, the said gear means including means for driving the said threaded spindle in either direction, a hollow spindle secured in the said top plate of the third housing, the said hollow spindle having inner thread and receiving the said threaded spindle, means disposed in the said second housing to guide the said hollow spindle in axial direction and to prevent rotation thereof upon turning the said threaded spindle, additional gear means disposed in the said first housing and operated by the said motor for turning the said first housing upon its vertical axis on the said base, and means for controlling the said additional gear means, and the said top plate of the third housing having supporting means adapted to support a drawing board or the like.

2. The structure, as set forth in claim 1, which includes relay means disposed adjacent the lower and upper ends of the said third housing in order to open the motor circuit upon reaching the lowermost and uppermost position, respectively, of the said third housing.

3. A pedestal structure comprising a base, a horizontally disposed bevelled gear secured to the said base, a vertically disposed pivot mounted in the said base, a first housing rotatably mounted upon the said pivot of the base, a second housing in superposed positions to the said first housing and a third housing having a top plate, being open at its bottom and telescopically receiving the said second housing, a motor supported by the said base, two oppositely arranged and vertically disposed bevelled gears freely rotatable on a horizontally disposed shaft supported by the base, the latter being driven by the said motor, a third horizontally disposed bevelled gear meshing both said vertically disposed bevelled gears, a vertically disposed screw spindle extending upwardly into the said second housing, the lower end of the said screw spindle being secured to the said horizontally disposed third bevelled gear, clutch means disposed between the said two vertically disposed bevelled gears to couple alternately one of the said last mentioned gears to the said driving shaft, the said screw spindle being mounted in the said second housing for rotation upon its longitudinal axis, a hollow spindle secured to the said top plate of the third housing, the said hollow spindle having inner thread and receiving the said screw spindle, guide means disposed in the said second housing to guide the said hollow spindle together with the said third housing for vertical movement of the latter relative to the said second housing, a pinion meshing the said bevelled gear secured to the said base, means for driving the said pinion by the said motor and means for controlling the said last mentioned driving means for the said pinion, the said pinion being adapted to turn the said housings relative to the said base, and supporting means secured to the top plate of the third housing adapted to support a drawing board or the like.
